UNITED STATES PATENT OFFICE

SAMUEL M. ANDERSON, OF SHARON, MASSACHUSETTS, ASSIGNOR TO B. F. STURTEVANT COMPANY, OF BOSTON, MASSACHUSETTS, A COMPANY

AIR CONDITIONING METHOD AND APPARATUS

Application filed June 21, 1930. Serial No. 462,778.

This invention relates to unit humidifiers and, more particularly, to unit humidifiers which may be used in small enclosures.

An object of the invention is to moisten air without noise.

Another object of the invention is to provide a unit humidifier without an auxiliary fan or rotating spray producing mechanisms.

Another object of the invention is to provide a small unit humidifier constructed on the atomizer principle.

Another object of the invention is to apply a silencer to a humidifier.

Another object of the invention is to provide a unit humidifier of the atomizer type with a self-contained liquid and air supply.

Another object of the invention is to provide a humidifying system utilizing unit humidifiers of the atomizer type having central compressed air and liquid supplies for operating unit humidifiers spaced throughout a building.

Other objects of the invention will be brought out in the following description of the invention, and its operation:

It is becoming better and better known that living conditions in heated rooms are greatly improved when the air within the rooms contains a substantial amount of moisture or water vapor which tends to prevent the drying of the nasal and throat passages of the occupants. This moisture also tends to prevent the circulation of dust, which in itself is undesirable and may be injurious. Also, in certain manufacturing processes, among which are the manufacture of paper and the manufacture of cloth, the presence of a certain amount of moisture is necessary in the air in which the processes are employed. The heating systems generally employed for heating buildings effectively reduce the relative amount of moisture in the air so that it has been found desirable to provide humidifying apparatus for introducing additional moisture to compensate for the loss of relative humidity through the heating process.

A great many theatres and manufacturing plants have humidifying systems combined with ventilating systems, the systems being built-in, so to speak, as a part of the buildings.

Such an arrangement is not always practical in office buildings, in homes, and in some manufacturing plants.

Heretofore, in rooms of buildings not having built-in humidifying systems, it has been customary, when it is desired to humidify the air, to employ small unit humidifiers of the type employing a rapidly revolving member against which a stream of water is impinged so as to throw off by centrifugal force against baffle plates, a water spray. Such humidifiers are unsatisfactory. They are noisy, require considerable attention, and are inefficient.

According to a feature of this invention, a unit humidifier is provided having no revolving members for producing a spray. The humidifier, according to this invention, operates on the atomizer principle. The compressed air stream is forced across the mouth of a water nozzle creating a suction within the water tube so as to draw water through the water tube, which at the mouth of the water tube, is converted into spray by the compressed air stream.

According to another feature of the invention, the atomized spray produced by the action of the compressed air stream is directed into a silencer of the Maxim, or other suitable type, to dissipate the noise of operation.

According to another feature of the invention, a unit humidifier utilizing atomizing nozzles has its own self-contained compressed air and water supply.

According to another feature of the invention, a central compressed air and water supply in the basement, or other suitable portion of the building, is provided, the water and compressed air being piped to each room, or portion of the building, where it may be desired to humidify the air. Then, unit humidifiers of the atomizer type, according to this invention, are provided in each of the rooms and connected to the compressed air and water piping.

The invention will now be described with reference to the drawings, in which:

Figure 1 is a side view partially in section of a unit humidifier, according to this invention;

Figure 2 is a top view of the water and compressed air nozzles utilized in Fig. 1;

Figure 3 is a sectional view through one form of a silencer which may be employed in the unit humidifier of Fig. 1;

Figure 4 is a sectional view along the lines 4—4 of the silencer of Fig. 3.

Figure 5 is a view showing a central compressed air and water supply with a number of unit humidifiers placed throughout the building;

10 Figure 6 is a side view in section of a unit humidifier of the atomizer type having a self-contained compressed air and water supply, and

15 Figure 7 is a sectional view along the lines 7—7 of Fig. 6.

Referring now to Fig. 1, the unit humidifier there shown comprises the container 10, which may be of sheet metal, or other suitable material, and which may be shaped to resemble a vase, or other decorative object. Within the container 10 is the air nozzle 11 through which a stream of compressed air is applied from an outside source; a water nozzle 12 through which water is drawn by 25 the compressed air through the nozzle 11 from the water reservoir in the base of the container 10, the silencer 13 into which the atomized spray, produced from the water and compressed air nozzles, is projected, and 30 the water supply pipe 14 which is controlled by the float valve 15.

The operation of the apparatus shown by Figs. 1, 2, 3, and 4, will now be explained. The water level in the reservoir at the bottom of the container 10 is maintained at a desired level by means of the float valve 15 which controls the introduction of water through the water supply pipe 14. Compressed air is forced through the nozzle 11 40 from an outside source, which compressed air passing across the mouth of the water nozzle 12 creates a vacuum therein and pulls the water from the storage base in the bottom of the container 10 through the water pipe 12 to the mouth thereof, where it is converted into an atomized spray by the pressure of the compressed air at that point.

Ordinarily, the passage of the compressed air produces a high pitched hissing sound, 50 which is undesirable. To prevent this, the atomized stream of water and air is projected into the lower portion of the silencer 13. A portion of the water spray is precipitated on the sound absorptive members 31, 32, 33, 55 34 and 35 of the silencer, and drains back into the reservoir, but a large portion exits without noise through the mouth 17 of the silencer.

60 The silencer 13, illustrated by Figs. 3 and 4, consists of a metal casing within which are supported the sound absorptive members 31, 32, 33 and 34. These sound absorptive members may be of felt, sponge rubber, or other suitable material, and each member has 65 an opening therein staggered with respect to

the openings in members on each of its sides. A large portion of the atomized spray is carried upwards through the openings in the said absorptive members and out the opening 17, but the sound waves are absorbed by the sound absorptive members. While this type of silencer is satisfactory, obviously other types of mufflers or silencers could be used with the humidifier.

It is seen that with this arrangement a simple, compact, and efficient humidifier of the unit type, is provided. According to this invention, the centrifugal pump, the rotating disk, and the fan blades of the present type of unit humidifiers, are done away with. The noise produced in the process of atomization is absorbed in the silencer so that no noise is introduced into the room by the operation of the device. The compressed air not only produces a finely divided spray, but carries the spray up into the room without the necessity of the usual fan.

The atomizer humidifier herein described may be of a portable type containing within its structure an air compressor and a water reservoir, this type being shown by Figs. 7 and 8, or may be of the type shown by Fig. 1, into which are fed water and compressed air from an outside source.

A humidifying system, according to this invention, may be built into a building without the necessity for a built-in ventilating system, which combination of systems is essential in present practice. With a humidifying system, according to this invention, one of the unit atomizer humidifiers may be installed in each room of a building where it is desired that the air be humidified, it only being necessary that water and compressed air piping be conveyed to, and have an outlet in each room. A central water supply, which may be from the city mains, provides the water to be atomized. A central air compressor or compressed air storage tank may be arranged in the basement, attic, or other suitable portion of a building. One embodiment of such a system is illustrated by Fig. 6. There, the several floors and several rooms of a building are illustrated schematically. Unit humidifiers 10 of the type described, in connection with Fig. 1, are placed in each room. In the basement of the building is placed a compressor plant which comprises the air compressor 18, the air intake of which may pass through the silencer 19, the compressed air storage tank 20, and the electric motor 21, which serves to drive the compressor 18. A compressed air line 22 passes from the compressor plant through the various floors of the building, branch air lines 23 being tapped to supply the various unit humidifiers 10. The water main 24 carries the water supply through the various floors of the building. The branch water lines 25 convey the water supply to each of the unit humidifiers 10. The

operation of the unit humidifiers 10 in this system is exactly the same as that described in connection with Fig. 1. Each of the unit humidifiers 10 can be individually controlled to provide the degree of humidity desired in its location. This control may be manual or automatic. The advantages of this system are seen to be many. There is no necessity for a complicated ventilating system for introducing moistened air. The air in each room of a building may be controlled exactly as desired. Replacements are easy and first cost is low.

This humidifying system, utilizing unit humidifiers spaced throughout a building with central water and air supply, lends itself, with few modifications, to buildings already constructed which have numerous suction connections for vacuum cleaners. As is well known, many buildings now have a central vacuum system with pipes leading from the central equipment to individual rooms or a series of individual rooms. The unit humidifiers of this invention may have their air intake connected with the vacuum piping, and the vacuum equipment in the central location can either be reversed to supply air under pressure to the unit humidifiers or an air compressor may be connected at the central location to the pipe lines to supply the desired air pressure.

It is realized that a system of air and water piping, such as that described in connection with Fig. 6, cannot always be employed in buildings already constructed, and that for rooms of such buildings it is desirable to have a portable type humidifier which may have a self-contained air and water supply.

One embodiment of such a humidifier is shown by Figs. 6 and 7. The electric motor 26 drives the small air compressor 27. The air for the air compressor 27 is drawn through the silencer 36 and after compression is fed through the air pipe 28 to the air nozzle of the humidifier. The base of the humidifier unit has a large water storage space into which water may be introduced through the opening 29. The operation of the unit humidifier is similar to that described in connection with Fig. 1, the compressed air passing through the water nozzle and producing at the mouth of the water nozzle an atomized spray which is directed into the silencer 30 from the mouth of which a large portion of the atomized spray is projected into the room without noise. Obviously, the unit humidifiers would not have to have the shapes shown by Figs. 7 and 8. It would be but a simple matter to disguise the appearance of the essential portions of the humidifier to present a pleasing appearance which could even be decorative.

The main feature of this invention is the elimination of noise in humidifiers. To this end, it is planned that sound insulating ma-

terial be placed at every place where sound might be produced or transmitted. Where the compressed air and water piping enters the unit humidifiers, it is planned to place sound absorptive material. The same material is to be used at every point of support of the silencer and of all other equipment.

Whereas one or more embodiments of the invention have been described for the purpose of illustration, it should be understood that the scope of the invention is not limited to any of the particular embodiments described, but only by the annexed claims.

Having described my invention, what I claim as new and desire to secure by Letters Patent, is:

1. A humidifier comprising a supply of liquid means for producing an atomized mixture of said liquid through the action of a compressed air stream, and means for reducing the noise from said first mentioned means. 85
2. A humidifier comprising an atomizer utilizing air under pressure, and a silencer for reducing the noise from said atomizer.
3. A humidifier comprising a silencer, and means for projecting an atomized spray of air and liquid into said silencer. 90
4. A unit humidifier comprising a container, a water reservoir, a water nozzle extending into said reservoir, a compressed air nozzle arranged to atomize water from said water nozzle, and a silencer arranged to receive the atomized water. 95
5. A portable unit humidifier comprising a water supply, means for producing compressed air, means for atomizing water from said supply by said compressed air, and means for reducing the noise from said second mentioned means. 100
6. A portable unit humidifier comprising a water reservoir, means for producing compressed air, means for atomizing water from said supply by said compressed air, and a silencer for receiving the atomized spray to reduce the noise resulting from the production of same. 105
7. An air conditioning system comprising a central compressed air supply, a central water supply, and a plurality of unit atomizer humidifiers connected to said air and water supplies. 115
8. A system for conditioning air in a plurality of locations comprising central compressed air and water supplies, piping between said supplies and each of said locations, and an atomizing humidifier in each of said locations connected to said piping. 120
9. A system for conditioning air in a plurality of locations comprising central compressed air and water supplies, piping between said supplies and each of said locations, and an atomizing humidifier in each of said locations connected to said piping, said humidifiers containing silencers for reducing the noise of operation. 125
- 130

10. An air conditioning system comprising a central compressed air supply, a central water supply, and a plurality of unit atomizing humidifiers connected to said air and water supplies, each of said humidifiers containing a silencer for reducing the noise of operation.

In testimony whereof I affix my signature.
SAMUEL M. ANDERSON.
